UNITED STATES PATENT OFFICE

IRA W. KNIGHT, OF PROVIDENCE, RHODE ISLAND, ASSIGNOR TO DETEX WATCHCLOCK CORPORATION, OF NEW YORK, N. Y., A CORPORATION OF DELAWARE

SUPERVISORY MECHANISM

Application filed November 28, 1927. Serial No. 236,152.

This invention relates to a supervisory mechanism for preventing the use of a recording instrument when the position of a device which is being reported upon by the use of 5 the recording instrument is in other than a normal desired position.

The supervisory mechanism is well adapted for use with a valve and in connection with automatic sprinkler systems. Because of the 10 desirability of knowing whether such a valve is open or shut, watchmen are employed for inspecting the same and it has been proposed that a watchman carry a recording clock adapted to be affected by a recording instru- 15 ment associated with a valve. The proposed scheme necessitates that the recording instrument at the valve be ordinarily arranged so that a watchman would be unable to produce a record if the valve be in a closed posi- 20 tion or partly closed position, and under such conditions the recording instrument at the valve would be maintained inaccessible.

Since the record carried by a recording clock conveys a definite story indicating the 25 diligence of the watchman and/or the condition of the valves when used in carrying out the scheme above outlined, it becomes necessary to have supervisory mechanisms at the valves which cannot be tampered with 30 and which will function with absolute cer- tainty.

Among the objects of this invention is to provide a supervisory mechanism of a simple construction which may be easily affixed to 35 an ordinary type of valve without the necessity of extensive alterations or changes in the permanent installation of the valve.

Another object resides in producing a supervisory mechanism of few parts which 40 nevertheless serves efficiently as a supervisory mechanism which cannot be circumvented without detection.

Other objects appear in the detailed de- 45 scription of the invention and in the claims.

Fig. 1 illustrates a sectional side view of a supervisory mechanism as affixed to an ordinary type of valve.

Fig. 2 illustrates an end view of the supervisory mechanism with its cover in place.

Fig. 3 is a sectional view of the supervisory mechanism taken on line 3-3 of Fig. 1.

Fig. 4 is an end view of the supervisory mechanism.

Fig. 5 is a sectional view taken on line 55 5-5 of Fig. 3.

The valve illustrated is intended to represent a type of valve generally known as an O. S. & Y. valve. This valve 10 has a yoke supporting the valve stem and rotating parts, 10 and the yoke comprises side-pieces 11, 12 ex- tending upwardly. The rotatable nut 13 is capable of being manipulated by means of a hand wheel 14 for the purpose of raising or lowering the valve stem 15. Movement of the valve stem causes the valve gate to be 60 opened or closed as is well understood.

The bracket or frame of my supervisory mechanism comprises a T-shaped member having oppositely extending flanges 16 and 17 which are slotted so as to enable the supervisory mechanism to be bolted or similarly fastened to the yoke of the valve. The supervisory mechanism is intended to be used with valves of different sizes so it is desired that 70 these flanges be of such length as to enable elongated slots 18, 19 to be formed therein.

Fig. 2 illustrates the manner in which this mechanism is intended to be affixed to a valve. The bolts 20 which are used should be such as to be capable of being locked when the mechanism is mounted in place. Ordinary sealed wires are suitable for this purpose. In the present disclosure of the invention the stem portion 21 of the T-shaped member is of 75 a hollow design which is closed at the flange and except for a hole 22 of sufficient size to permit longitudinal movement of a rigid- body member or bar 23 therethrough.

Extending from the open end of the hollow stem is a recording instrument or key 24, the base portion of which is supported within the hollow stem 21 and is held therein by bolt 25 extending through opposite walls of the hollow stem and through the base portion of 95 the recording key. It is desirable that this bolt be permanently locked in place by some device such as a sealed wire in order that the key may not be removed at will from its permanent location within the hollow stem, Fig. 100

3. The recording instrument itself does not form a specific part of this invention for it is contemplated that any well known type of recording key may be used. However, reference may be had to the United States reissue 5 Letters Patent No. 14,193 for a form of key which is well adapted for use in this particular supervisory mechanism. For the purpose of understanding the present invention it is 10 only necessary to know that the shank of a watchman's time recorder or patrol clock must fit over the recording key 24 for a definite length of the key before the key may be operated to produce a record. My invention 15 involves mechanism which will prevent a record being produced in the manner outlined under certain conditions, and accomplishes the desired result by relative positioning of some adjacent member or bar 23 and 20 recording key 24. While the recording key 24 could be movable, in the present disclosure it is permanently anchored within its bracket or frame.

When affixing the supervisory mechanism 25 to a valve it is necessary that the valve stem 15 be slotted in order to accommodate the stem end of the bar 23 for a predetermined position of the valve as when the valve is in an open position. For the purpose of the 30 present disclosure it is intended that the valve be entirely open when the bar 23 is capable of entering within the slot 26, as illustrated in Figs. 3 and 5. The slot 26 should be only long enough to accommodate the end of the 35 bar 23 when the valve is fully open, but it is readily understandable that the slot in the stem 15 could be lengthened or variously placed so as to enable the recording mechanism to be operated for other than a fully 40 opened position of the valve. However, in its adaptation for use with sprinkler systems, it is desirable to be able to make a record on a watchman's recording clock whenever the 45 valve is fully open and under no other conditions. As has been pointed out hereinbefore, a watchman in making his rounds will carry with him a recording clock which has a hollow shank 27 adapted to be fitted over the 50 working end of recording key 24, as in Fig. 3. The length of the stem portion 21 in relation to the length of the recording key is such that the shank 27 of the recording clock may be 55 fitted over the recording key and thereby cause a record to be produced upon the dial of the recording clock, Fig. 3. Should it not be possible to advance the shank 27 of the recording clock to its full distance over the 60 working end of the recording key, as shown in Fig. 3, then it would not be possible to produce a record on the recording clock carried by the watchman. The bar 23 is designed 65 for accomplishing this objective by rendering the recording key inaccessible for record producing purposes.

When the valve stem 15 is in other than a fully opened position, the stem end of the bar 23 will come up against the largest or threaded portion of the stem 15 and the key end of the bar 23 will extend beyond the open end 70 of the hollow stem 21. Under these conditions it will be impossible to fit the shank 27 of the recording clock to its operable position about the recording key because of obstruction by the bar 23. Accordingly, it will 75 be impossible for the watchman to make a record upon the dial carried within the patrol clock, and by reading the dial one will be informed that at a scheduled time the valve was either not fully open or else the watchman failed to make proper inspection. In either event it would be necessary to inspect the valve in order to open it should it be found to be closed. Presumably if a watchman found that he was unable to make a record when he made his inspection, he would open the valve and thereby render the supervisory mechanism operative for the purpose of permitting a record to be made. The 80 patrol clock dial would show that the valve 90 was open at the time of the last inspection, the desired condition of the valve.

For the purpose of affording protection for the recording instrument 24 there is provided a cover 28 which is adapted to be slid over the 95 hollow stem 21 and fully protect the recording key from weather conditions. Slots are provided in this cover in order to accommodate the various flanges and the outer extremities of the bolt 25. A chain 29 may be provided for the purpose of keeping the cover 100 in condition for supervisory mechanism.

I wish it to be understood that I do not 105 restrict myself unessentially with the foregoing description but contemplate such changes and modifications within the scope of the appended claims as may be found to be advisable.

What I claim is:

1. A supervisory mechanism comprising, 110 in combination, a recording key, a bracket for supporting said recording key, and means mounted adjacent said recording key and adapted to be positioned in respect to said recording key to prevent operation thereof without changing the position of the key relative to said supporting bracket.

2. A supervisory mechanism comprising, 115 in combination, a recording key, a bracket, means for supporting said recording key on said bracket, and a rigid-body member supported by said bracket alongside of said recording key, said member being positionable relative to said recording key whereby it may 120 obstruct operation of said recording key for recording purposes.

3. A supervisory mechanism adapted to be 125 affixed to a valve having a longitudinally movable stem and comprising a frame mem- 130

ber having a plurality of flanges by which said frame member may be affixed in definite relation with the valve, a recording key, means extending from said flanges for supporting said recording key, and a bar carried by said means and mounted so as to permit movement thereof relative to said recording key, said bar being of such length in respect to said recording key as to render said recording key inoperable when said bar contacts the outside surface of the longitudinally movable stem.

4. A supervisory mechanism adapted to be affixed to a valve having a longitudinally movable stem and manipulative means for moving the stem comprising, a T-shaped member with oppositely extending flanges having slots therein whereby said member may be affixed to the valve, said T-shaped member having a hollow central stem, a recording key having one end thereof permanently fixed within said hollow stem and a bar adjacent said key and slidably mounted within said hollow stem and adapted to extend beyond the end of said hollow stem for the purpose of preventing operation of said recording key by a recording clock.

5. A supervisory mechanism adapted to be affixed to a valve having a longitudinally movable stem and manipulative means for moving the stem comprising, a T-shaped casting having means whereby said casting may be permanently affixed in relation to the valve, a stem comprising a portion of said casting, a recording instrument having one end supported by said stem, and a bar slidably mounted on the stem, the movable stem of the valve having a notch for accommodating the end of said bar, said bar being of such length as to permit operation of said key when the other end of said bar is opposite said notch.

6. A supervisory mechanism adapted to be affixed to a valve having a longitudinally movable stem and manipulative means for moving the stem comprising, a T-shaped member with oppositely extending flanges and a hollow central stem, a recording key having a portion thereof extending from within said hollow stem, and a bar slidably mounted adjacent said recording key, said bar being extendable beyond either end of said hollow stem and being of such length as to extend beyond the end of said hollow stem when the bar is in contact with the surface of the movable valve stem.

7. A supervisory mechanism comprising, in combination, a bracket, cooperatively related members including a recording key and rigid-body member, and means supporting said recording key and said rigid-body member on said bracket and in sliding relation to each other, said means providing rigid support on said bracket of one of said members.

8. A supervisory mechanism adapted to be affixed to a valve having a longitudinally movable stem and manipulative means for moving the stem comprising, a frame member, a recording key, means extending from said frame member and rigidly supporting said recording key, and a bar carried by said means and mounted so as to permit movement of the bar relative to said recording key, said bar being of such length in respect to said recording key as to render said recording key inoperable when said bar contacts the outside surface of the longitudinally movable stem.

In testimony whereof I hereto affix my signature.

IRA W. KNIGHT.
